UNITED STATES PATENT OFFICE.

SAMUEL D. MADDIN, OF MIAMISBURG, OHIO, ASSIGNOR TO MARY MADDIN,
OF SARNIA, ONTARIO, CANADA.

HARVESTER.

SPECIFICATION forming part of Letters Patent No. 403,764, dated May 21, 1889.

Application filed July 9, 1885. Serial No. 171,135. (No model.)

To all whom it may concern:

Be it known that I, SAMUEL D. MADDIN, a citizen of the United States, residing at Mi-
amisburg, in the county of Montgomery and
5 State of Ohio, have invented certain new and
useful Improvements in Harvesters, of which
the following is a specification.

My invention consists in certain improve-
ments in harvesting-machines, illustrated in
10 the accompanying drawings and fully set
forth hereinafter, having for their object to
facilitate the conveying of the grain from the
cutters to the binder, to secure an easy and
effective adjustment of all the parts from the
15 driver's seat, to increase the general efficiency
of the implement, and overcome certain ob-
jections incident to harvesters of the ordinary
construction.

In the drawings, Figure 1 is a front eleva-
20 tion, in part section, of a harvester embodying
my improvement. Fig. 2 is a rear elevation
showing the frames, supporting-wheels, and
some of the parts. Fig. 3 is a side view illus-
trating the connection of the main frame and
25 pole. Fig. 4 is a plan of Fig. 3. Fig. 5 is a
rear elevation illustrating the connection of
the frames and part of the elevating appli-
ances. Fig. 6 is a partial plan of Fig. 5. Fig.
7 is a part front elevation. Fig. 8 is a plan
30 showing the outer end of the grain-platform
frame, supporting - wheel, and connections.
Fig. 9 is a sectional elevation on the line 1 2,
Fig. 8. Fig. 10 is an enlarged plan illustrating
the construction of the grain-conveyers.
35 Fig. 11 is a sectional side view of one of the
conveyer-arms. Fig. 12 is a side view of one
of the said arms. Fig. 13 is a sectional plan
illustrating the arrangement of gears between
the driving-shaft and conveyer-arms. Fig. 14
40 is a detached view, in side elevation, showing
the mechanism for throwing out of operation
the grain-conveyers. Fig. 15 is a perspective
view of a portion of one of the elevator aprons
or belts.

45 To avoid confusion I have illustrated in
the different views only such of the parts as
are required to facilitate the description of
the machine.

The frames of the machine are supported

by wheels A A' A², the wheels A A' turning 50
upon or with an axle, B, extending through
a sleeve, B', forming part of the frame or sup-
port C of the binder, to which frame is hung
one end of the frame C', the opposite end of
55 which is connected to the frame C², support-
ing the cutters and grain-platform, the outer
end of the said frame C² being supported by
the wheel A².

As the frame C' is jointed both to the frame
C and to the frame C², it is necessary to em- 60
ploy means for supporting the inner end of
the latter frame. I therefore suspend the same
at front and rear by means of rods or chains
C³ at the outer ends of arms C⁴, connected to
a shaft, C⁵, turning in bearings upon the frame 65
C, and I use suitable appliances whereby the
shaft C⁵ may be turned to raise and lower the
inner end of the frame C², and I also prefer
to so connect the frame C² with the wheel A²
that the outer end of the frame C² will be 70
simultaneously raised and lowered with the
inner end, thereby maintaining the frame
and cutters horizontal while permitting their
adjustment to any desired height.

One means of lifting the frame C² consists 75
in providing the shaft C⁵ with an operating
handle or lever, C⁶, the end of which is ad-
jacent to the seat C' of the driver, which is
supported upon a spring-bar, C⁸, connected to
the rectangular body H of the frame C, the 80
lever C⁶ being secured in any desired position
by bringing it against any one of a series of
teeth or shoulders, X, upon a standard, C⁹,
upon the frame C. I prefer, however, to use,
instead of the lever C⁶, or in connection there- 85
with, a drum, C¹⁰, Figs. 2 and 4, turning in
bearings upon the frame C and operated by
means of a lever, C¹¹, and pawl and ratchet,
and receiving a chain, C¹², extending to the
lever C⁶, so that the shaft C⁵ may be turned 90
in the direction of its arrow by winding the
chain C¹² upon the drum, and turned in a re-
verse direction by unwinding the chain.

To secure the simultaneous equal move-
ments of both ends of the frame C², the jour- 95
nal of the wheel A² is carried by a lever, D,
pivoted at the front end to the adjacent side
of the frame C², near the forward edge thereof,

and connected by a chain, D', passing round guide-pulleys D² D³ to an arm, C¹⁷, projecting from the shaft C⁵. By this arrangement the turning of the shaft C⁵ in the direction of its arrow, Fig. 2, directly lifts the inner end of the frame C², and by drawing upon the chain D' depresses the lever D and lifts the outer end of the frame, which thereby rises and falls while maintaining its horizontal position.

10 I have referred to the rods C³ as being connected at their lower ends to the frame C²; but it will be obvious that the same effect will be secured by connecting the rods to the frame C'.

As it is important to alter the angle of the 15 frame C², as well as to raise and lower it, I effect this latter adjustment by swinging the frame C upon its axle, as will be hereinafter set forth; and in order that the tilting movement of said frame C may be conveyed without lost 20 motion to said frame C², I connect the two frames in front and in rear of the wheel A at y' y², and I brace the frame C', so that it will not twist or spring. Thus the frame C', Figs. 2, 5, and 6, consists of the end bars, b b', each 25 having its outer end pivoted by bolts b⁴ to lugs b', upon portions of the frame C, and being connected to a brace, b², the outer ends of both braces being bolted loosely to a lug, b³, on the sleeve B', by a bolt, b⁵, in line with 30 the bolts b⁴.

To better balance the grain-platform C², as well as to facilitate its elevation and to maintain its weight upon the wheel A, should it strike upon the ground at points between the 35 wheels A and A² and thereby be raised above its normal position, I counterbalance the weight of said platform C² to a greater or less extent by means of a counterbalance weight or spring. Thus a weight, b⁶, may be secured 40 adjustably to the lever C⁶ in such a position as to nearly counterbalance the weight of the inner end of the frame C², or a spring, b⁷, Fig. 4, may be bolted to the frame C at one end and at the other to a disk, b⁸, Figs. 1 and 4, turning 45 upon the shaft C⁵, and provided with notches w, adapted to receive a detachable pin, b⁹, passed through a hole in the arm C⁴, so that the said disk may be turned to apply any desired tension to the spring, and then 50 secured in place by means of the pin, the spring acting in the same manner as the weight. By this construction it will be apparent that the weight of the platform will be maintained at all times upon the wheel A.

55 The tilting of the frame C is effected by pivoting the pole Z, Figs. 3 and 4, to the front of the frame C by a bolt, c', which passes through ears 21 21, and by operating upon an arm or extension, Z', of the pole to raise and 60 lower the same. This extension is carried to one side of the binder-frame below the binder-table in the form of a bent plate pivoted at c to a projection upon the frame C, in line with the pivot c' of the pole, and carried parallel to 65 the side of the frame C and bent at the end to form a handle extended to a position adja-

cent to the driver's seat, a bolt, c², carried by the lever-extension, serving as a means of locking the same in any desired position upon a curved lock-plate, c³, secured to the frame. 70 C. The arm Z' thus serves not only as a lever, but as a brace to the pole, of which it constitutes an extension. The driver thus by manipulating the lever C¹¹ can raise and lower the grain-platform frame vertically, and 75 by manipulating the lever Z' can tilt it so as to carry its forward edge to or from the ground, thus imparting any desired angle to said platform.

As it is essential to retain the relative positions of the grain-platform frame C² and the binder, while permitting the adjustments before described, I support the binder (see Fig. 1) between the wheels A and A' upon the frame C, so that the binder will move with 80 said frame C and with the other frames connected to it, and I arrange the elevators so as to convey the grain from the grain-platform C², over the wheel A, to the upper edge of the table A⁴ of the binder, whatever may be the 85 relative positions of said binder and platform C², and I extend the said table A⁴ over the wheel A', so that the grain discharged from the table will fall outside of said wheel.

The grain-elevator may be of any suitable 90 construction. As shown, it consists of two frames, E E', pivoted together, and frame E², overlying and hinged to the frame E. The frame E is pivoted to the frame E' at its upper end and at its lower end to the grain-platform frame C², while the frame E' is pivoted at its outer end level with the table A⁴ between two standards, C⁹, upon the frame C. The pivotal shafts c⁸ c⁴ of the frame E carry the drums d d, Fig. 2, round which 100 passes the elevator-belt d', and the frame E² carries shafts c⁵ c⁶, supporting drums d² d², round which passes an elevator-belt, d³, between which and the belt d' the grain is carried upward from the grain-platform carrier-belt d¹³ and delivered onto the inner end of the binder-table A⁴.

The power to turn the elevator-belts is applied to a sprocket-wheel, c⁷, Figs. 7 and 10, upon the forward end of the shaft c³, as will 115 be hereinafter described, and gear-wheels c⁸ upon the shafts c³ c⁵ intermesh, so as to insure the coincident movements of the two belts d' d³.

Motion is transmitted from the uppershaft, 120 c³, of the elevator E to the shaft d⁴ of the grain-platform carrier-belt roller d⁵, (see Figs. 5 and 6,) through the medium of sprocket-wheels d⁶ d⁷ and a sprocket-chain, d⁸, connecting said wheels and carrying pins d⁹. 125 The sprocket-wheel d⁶ is mounted upon the projecting end of the shaft c³, while the sprocket-wheel d⁷ turns upon a journal which projects from a bracket, F, (see Fig. 6,) secured to the grain-platform frame C², and 130 carries a gear-wheel, e, which imparts motion to a gear-wheel, e', through the medium of an

intermediate gear, e^2 , the gear e' being upon the shaft d^4 of the carrier-belt roller d^5 .

The sprocket-wheel d^6 is placed at some distance beyond the side of the frame E , Figs. 6 and 10, and an inclined guard-plate, F' , slotted for the passage of the pins d^9 , extends from the side of the frame E beyond the chain d^8 , and constitutes, practically, an extension of the inclined belt of the elevator, so that the pins d^9 of the sprocket-chain will co-operate with the elevator-band in lifting long grain. The sprocket-chain d^8 therefore serves the double purpose of an elevator and a band communicating motion to the grain-platform carrier-belt roller d^5 .

In order that the grain may be carried up between the two elevator-belts and extend beyond the frame E^2 to the sprocket-chain, it is necessary that the frame E^2 shall be connected to the frame E only at the forward end, and in order that the upper elevator-belt may always press upon the grain, whether the body of grain be thick or thin, and avoid too great a pressure when the body of grain is thick, I connect the frames E E^2 by means of hinges e^4 , Figs. 1 and 7, which maintain the frames in proper relative position, but permit the upper frame to be swung outward to accommodate the amount of grain passing through the elevator, and also permit the rear of the upper frame to swing farther away from the lower frame to accommodate the heads of the grain.

As there is necessarily a space between the adjacent ends of the grain-platform carrier-belt d^{13} and the elevator-belt d' at the point x^3 , (see Figs. 1 and 6,) stalks of grain frequently pass through to the ground. To avoid this waste, I provide the band d' with a series of flaps or flexible strips, e^5 , of leather, rubber, or other suitable material, (see Figs. 1, 6, and 15,) each extending across the band and secured thereto at one edge by rivets or equivalent means, which flaps are thrown outward by the movement of the band, so as to close the opening x^3 as they pass through the same, and catch and throw back any of the stalks which would otherwise escape, thereby insuring the lifting of the entire amount of grain that is cut.

The grain discharged from the elevator is thrown onto the upper end of the table A^4 , down which it is carried by the teeth e^6 of conveyers e^7 , arranged above the table and carried by sprocket-wheels e^8 e^9 , (see Figs. 10, 11, and 12,) grain thus being fed forward to a position to be caught by the grain-binder packers. As the grain varies in length, it is of course desirable to shift the same, in order that it may be brought to the proper position to be operated upon by the packers and binding-arm, and this has ordinarily been done by means of a guide-plate, F^2 , to engage the butts of the grain, which plate is set at an angle to a greater or less degree, according to the extent to which the grain is to be shifted.

It has been found, however, that the grain does not move freely to its required lateral position under the action of such a guide-plate. To overcome this defect, I so hang the conveyers above the table A^4 or the movable platform A^4 , carried by the frame E' , that they may be set to the same angle as the guide-plate, so as to feed the grain positively at any required angle upon the table.

Different means may be employed for suspending and shifting the conveyers. I have shown one which I have found to be effective, the same consisting of slotted arms F^3 , each carrying at its opposite ends, respectively, the sprocket-wheels e^8 e^9 , which support and operate one of the conveyers e^7 , and each pivoted at points x^4 between said sprocket-wheels to a hub or casing b^8 , mounted upon a shaft, f , so that the frame F^3 and conveyers may be swung to any desired angle above the platform by means of a handle extending to within convenient reach of the driver and provided with any suitable locking device, the two arms being connected by a link, e^{19} , to each other, and the link being connected by a rod, e^{18} , to the guide-plate F^2 , so that both conveyers, frames, and the guide-plate F^2 will be maintained parallel in all positions.

The sprocket-wheels e^8 e^9 are driven from the shaft f , which is carried by standards f' , which project from the frame E' , by pinions f^2 within each of the casings f^x upon said shaft, each of which pinions gears with a pinion, f^3 , upon the shafts of the sprocket-wheels e^8 . By this arrangement each conveyer-arm F^3 is hung to the shaft f , so that it may be swung thereon to bring the conveyers over the table A^4 , or to carry them away from the said table, while the arms may be set to any desired angle without disconnecting the gears f^2 f^3 , since the pivots x^4 are substantially in line with the engaging portion of the gear-wheels, the guide-plate being kept parallel to the arms.

In order to insure a more uniform action of the gears, the former f^2 are provided with teeth having beveled corners, which engage the gears f^3 in the manner of bevel-gear when the conveyers are swung to one side, as shown in Fig. 13.

The suspension of the grain-platform frame C^2 from the binder-frame C by adjusting means renders it necessary to connect the elevator flexibly with the binder-table through the medium of a movable frame E' , as described, and this flexible connection has the advantage of permitting said platform-frame C^2 to be thrown upward to nearly a vertical position, so that the machine may be moved through a narrow gate or passage way without disconnecting or interfering with any of the parts, so that when the grain-platform C^2 is turned down to its horizontal position all of the parts will be in working condition, and by placing the conveyers upon the frame E' the adjustment of the parts above described

can be effected without interfering in any way with the operation of said conveyers.

As it is not desirable to feed the grain as rapidly toward the packers during the time 5 that the gavel is being packed and compressed as at other times, I provide means for lifting the conveyers or arresting their action at such times as it is desirable to arrest the flow of the grain. The movements of the 10 conveyers may be arrested by stopping the rotation of the shaft f ; but I prefer to continue the movements and to arrest the action of the conveyers by lifting their outer ends away from the table A⁴¹. One means of effecting this is illustrated in the drawings, (see 15 Figs. 1, 10, and 14,) and consists in connecting an arm, f^4 , projecting from the casing b^8 , by means of a rod, f^5 , to a crank, f^6 , upon a shaft driven by or from any moving part of 20 the machine. As shown, the said shaft is a prolongation of a shaft, 3, so that at each revolution of the latter the shaft f is rocked and the conveyers lifted from the table. While I have shown the arm f^4 as projecting 25 from but one of the casings or hubs b^8 , it will be understood that said casings may be connected together by a sleeve. (Shown in Fig. 10 by dotted lines as inclosing the shaft f .)

In order that the conveyers can be turned 30 back and away from the table without necessitating the withdrawal of connecting-bolts, I use a detachable connection with the operating parts. Thus I fork the end of the rod f^5 , so as to receive a pin upon the arm f^4 , which 35 pin can thus slip from its position between the fork when the conveyers are turned back, and can be inserted and brought into operative connection with the crank f^6 when the conveyers are brought into working position.

40 Motion is imparted to the shafts c^3 and f from the shaft 2, Fig. 7, which carries a sprocket-wheel, f^7 , round which and round sprocket-wheels g and c^7 passes a sprocket-chain, g^8 , the said chain passing also over a 45 tightening-roller, g^4 , hung to an arm, g^5 , pivoted to the forward standard, C⁹, and borne upon a spring, (not shown,) which tends to raise it and maintain the chain taut, whatever may be the position to which the frame 50 E' is adjusted.

It will be evident that the frames above described may be constructed of wood or metal in different ways, so as to impart the desired 55 rigidity, and that the adjusting devices, gears, and connections may be somewhat varied without any change in the main features of the parts described, whereby the platform-frame may be adjusted by the driver to any desired height without altering its horizontal 60 position and tilted without twisting by the tilting of the binder-frame, and whereby the grain may be carried over the inner wheel and delivered upon the table and directed to any desired position upon the latter, and 65 whereby the feeding of the grain onto the table may be arrested at intervals.

It will be seen that the binder occupies practically a stationary position between the wheels A and A', while the grain-platform frame can float over the ground at any angle, 70 and that the said frame may be adjusted vertically independently of the binder, so that the movements of the latter in binding and discharging the grain are not in any way affected by the position of the grain-platform frame, as results when the latter also carries 75 the binder.

To cover the grain as it is being moved forward by the packers, I use a guard, 33, which is hinged to a shield, 32, carried by the overhanging arm O of the binder, (see Fig. 1,) so that the said guard may be thrown back out 80 of the way in order to expose the table.

It will be evident that many of the devices above described may be used in connection 85 with binders of different constructions.

While I have shown and described in this application features also shown and claimed in a separate application, Serial No. 147,652, I do not here make any claim to the same. 90

Without limiting myself to the precise construction and arrangement of parts shown, I claim—

1. The combination, with the grain-platform frame, of a grain-elevator composed of 95 upper and lower frames connected together at their forward sides only by means of hinges, which permit the upper frame to accommodate itself to the mass of grain being elevated, and each provided with a positively-driven traveling grain-carrying apron, and driving-gears connecting the upper apron-drums at the forward sides of the elevator-frames, whereby the upper frame may move away from the lower frame at the rear side to accommodate 100 the grain without disengaging the driving-gears, substantially as described.

2. The combination of the platform-frame provided with a horizontal grain-carrying apron, an inclined elevator-belt, between 110 which and the horizontal apron there is an open throatway, and loose flaps upon the elevator-apron passing through the said throatway, substantially as set forth.

3. The combination, with two traveling 115 grain-carrying aprons arranged at angles to each other and with their ends adjacent to each other and separated by a throatway, of flexible strips e^6 , carried by one of the said grain-carrying aprons to bridge the said throatway, substantially as described.

4. The combination, with the binder-frame and a platform-frame, of an intermediate frame pivotally connecting the binder and platform frames and composed of lateral bars 125 b , pivoted both to the binder-frame and to the platform-frame, and the diagonal bars b^2 , arranged between the bars b and pivoted to the binder-frame in line with the pivotal connections of the bars b therewith, substantially as described.

5. The combination of the table upon which

the grain is delivered by the elevators, the shaft f , arranged above the table, the bracket b^8 , supported on the shaft, the frame F^3 , pivotally connected with the bracket, gear-wheels arranged between the said shaft and a shaft carried by the said frame, and a conveyor-chain driven by the last-named shaft, substantially as set forth.

In testimony whereof I have signed my name to this specification in the presence of 10 two subscribing witnesses.

SAMUEL D. MADDIN.
